UNITED STATES PATENT OFFICE

148,719

DESIGN FOR A HAIR CURLING DEVICE

Mario Petitta, New York, N. Y.

Application May 29, 1947, Serial No. 139,352

Term of patent 3½ years

(Cl. D86—10)

To all whom it may concern:

Be it known that I, Mario Petitta, a citizen of the United States of America, residing in New York city, county of New York, and State of New York, have invented a new, original, and ornamental Design for a Hair Curling Device, of which the following is a specification, reference being had to the accompanying drawing, forming part thereof, wherein,

I claim:

The ornamental design for a hair curling device, substantially as shown.

MARIO PETITTA,
